TIMING APPARATUS

Harry J. Atticks, Mechanicsburg, Pa.

Application July 6, 1933, Serial No. 679,257

5 Claims. (Cl. 161—1)

The invention relates to a variable timing apparatus adapted to close the operating circuit of a translating device or mechanism and maintain the closure for a predetermined and selected time interval, the breaking of the circuit being effected by a synchronous or constant speed motor, which operates an adjustable trip, which, at the end of the selected time interval, releases the switch from the locking means actuated simultaneously with the closing of the switch, with means for resetting the trip to its initially adjusted position, so that the translating device may be operated repeatedly for each selective setting of the apparatus and the duration of each operation may be accurately regulated as to time.

The invention is illustrated in the accompanying drawings, in which:—

Fig. 1 is a side elevation, partly in section, of the apparatus with the cover removed.

Fig. 2 is a plan view.

Fig. 3 is a section on line 3—3 of Fig. 1.

Fig. 4 is an enlarged horizontal section showing certain details.

Fig. 4^a is an elevation of the spring motor.

Fig. 5 is a section on line 5—5 of Fig. 4.

Fig. 6 is an enlarged side elevation of part of the trip device.

Fig. 7 is an end elevation thereof.

Fig. 8 is a perspective view of the entire apparatus, including the casing.

Fig. 9 is a general perspective of the principal operating parts of the mechanism.

Fig. 10 is a diagram of the circuits.

Fig. 11 is a front elevation of a shutter operating device adapted to be operated by the timing apparatus.

Fig. 12 is a lateral sectional elevation of the same.

Fig. 13 is a plan view thereof.

Referring to the drawings, 1 indicates the base of the apparatus, which is formed as a hollow casting having secured to the inner face of its top a block of insulation in which is mounted the binding posts or connectors for the various circuit leads. Secured to the top surface of the base is a framework comprising front and rear plates 2 and 3, which are connected together by cross bolts 4. Supported by spacer members 6 and channels 5' is a glass panel 5, which is parallel with the front plate 2, and serves to protect the indicia carried by the front plate, as will be pointed out hereinafter. Associated with the base 1 and the frame carried thereby is a cover 7 provided with a

front sight opening 8 and a handle 9, which is secured to the top and extends downward and is locked to the base by nuts engaging the threaded ends of the handle.

Secured by spacer bolts 11 to the rear plate 3 is a synchronous or constant speed motor 10, which is preferably of the type commonly employed in electric clocks operated by alternating currents of commercial circuits, the motor driving a chain of reducing gearing, the final member 12 of which meshes with a pinion 13 fixed to shaft 14 journaled in the plates 2 and 3 and carrying on its forward end a hand or index 15, which corresponds to the second hand of a clock and associated with a dial 16 on the front plate 2, said dial having a seconds scale thereon, the motor driving the shaft 14 at the rate of one complete revolution thereof per minute, so that the hand 15 travels around the dial 16 once every minute.

Secured to the back plate 3 are spaced brackets 21, 21 connected together by tie rods 22, between which brackets is mounted a solenoid 20 provided with a surrounding casing or armor 20'. Cooperating with the solenoid 20 is a core 23, to the upper end of which is attached a rod 24 extending through an opening in the top bracket 21 and carrying on its threaded end set nuts 25, which limit the downward movement of the core 23. Pivoted to the lower end of the core 23 is a link 26, the lower end of which is, in turn, pivoted to a rock lever 27 fixed to a longitudinal shaft 28 journaled in bearings in the lower portions of the front and rear plates 2 and 3, as more particularly illustrated in Fig. 1. The lever 27 is connected to link 29, which is connected to the outer end of a rock lever 30 secured to a sleeve 31 loosely mounted on the shaft 14, said sleeve having secured to its forward end a plate 32 provided with spring clips 33, 33, which support the tubular member 34 of a mercury switch, which tubular member is provided with two downward extensions 35 and 35' in which are sealed the ends of circuit wires, the parts being so arranged

that, when the solenoid is energized and the core 23 elevated, the tube of the mercury switch will be locked in the position shown in Fig. 3, so that the body of mercury in the main part of the tube will bridge the smaller bodies of mercury in the nipple-like extensions 35 and 35' and close the circuit between the wires sealed in said extensions, thereby closing the circuit from the source of electric current to the translating device or mechanism, which is to be operated for

45

a predetermined time, as will be more particularly explained hereinafter.

Mounted on a lateral extension of the upper bracket 21 is an insulating block 36, to which is secured two leaf spring terminals 37 and 37' interposed in one of the main circuit leads to the solenoid 20, which terminals are adapted to be bridged by a metal pin 41 mounted in a rock lever 40 secured to a shaft 38, which is journaled in the plates 2 and 3, respectively, said rock lever 40, leaf spring terminals 37 and 37' and bridging contact 41 constituting a switch or circuit breaker to interrupt the circuit of the solenoid, when the core 23 of the latter has completed its upward movement, as will be more particularly described hereinafter.

Secured to the rear plate 3 by spacer bolts 46a is a casting comprising a generally triangular plate 45 having formed integrally therewith a cylinder 47 disposed in horizontal relation and extending toward the front plate 2, the forward end of said cylinder having a central opening therein. The end of the casting toward the rear plate 3 is closed by a casing 45', which is secured to the plate 45 by screws and has projecting from its inner face and located axially within the cylinder 47 a hollow boss 48 provided with screw threads on its outer surface, which screw threads are engaged by a threaded nut 49 having gear teeth 50 on its periphery and also having a forward helical extension 51, which constitutes a yielding stop or detent. Extending through the central opening in the casing 45' is a sleeve 52, which is pinned to a longitudinal shaft 53, the forward end of which is journaled in the front end of the screw threaded boss 48. The pin connecting the sleeve 52 to the shaft 53 also secures thereto and to the shaft a clutch disk 54, the operating face of which is preferably serrated and is adapted to cooperate with a washer of leather or other flexible material mounted in the coordinate face of cooperating clutch member 55, which is loosely journaled on the shaft 53, said clutch member being provided with a toothed gear 56, which meshes with the gear 12 in the train of gearing driven by the synchronous motor 10, as hereinbefore described. The rear face of the clutch member 55 is provided with an inwardly beveled face 57 with which cooperates the coned or beveled head 58 of a sleeve 58', said head 58 also constituting a collar by means of which the clutch member 55 is released from engagement with clutch member 54. The sleeve 58' telescopes with an exteriorly threaded thimble 61, which is adjustably mounted in an interiorly threaded socket 60 secured to the outer face of the rear plate 3 and is locked in adjusted position by a set nut 62. Telescoping in the sleeve 58' is a bushing 63 having a beveled shoulder which engages a beveled shoulder on the interior of thimble 61, when the clutch members are disengaged, and an interiorly beveled end engaging the coned end of a nut 65, on the threaded end of shaft 53, when the clutch is in engaged relation, said nut being held in adjusted position by set nut 66. The bushing 63 serves as the outer abutment for a helical spring 64 which surrounds shaft 53 and snugly engages the inner wall of sleeve 58', the opposite end of said spring abutting the head 58, so that the normal tendency of the spring is to force clutch member 55 into engagement with member 54 and couple shaft 53 to the motor 10. The outer end of the shaft 53 is journaled in a bracket 53' secured to the

rear plate 3. This particular coordination constitutes means for normally engaging the clutch members 54 and 55 with each other through the action of the spring 64, but which will permit the clutch member 55 to rotate freely, when disengaged from clutch member 54, without imposing any undue stress on the motor spring 106, hereinafter described. While there is no positive connection between the head 58 and the clutch member 55, it is found, in actual practice, that the movement of the sleeve 58' to disengage the clutch members will effect this result apparently by reason of the slight cohesive effect of the lubricant between the coned surface of the head 58 and the beveled recess 51 in the clutch member 55.

Secured to the forward end of the shaft 53 is a cage-like element comprising annular members 67 connected by a series of bars 68 and slidably mounted on the bars 68 is a nut 69 having a radially projecting arm 70. The forward end of the cage-like element is journaled on the boss 72 formed as an integral part of a screw threaded stud 71, which is fixed in a plate 74 closing the forward end of the cylinder 47, said screw threaded stud being secured in position by nut 73. The nut 69 engages the threads on the stud 71 and, as the latter is stationary, the rotation of the nut 69 will cause the latter to move axially of the stud 71 so that one complete rotation of the shaft 53, when driven by the synchronous motor 10, and, therefore, one complete rotation of the nut 69 on the stud 71 will be effected in one minute. Normally the outer end of the radial arm 70 rests against the end of the helical extension 51 of the toothed nut 49, which is mounted on the threaded boss 48 and is moved out of engagement with the end of said helical member, when the shaft 53 is driven by the motor 10. The adjustment of the toothed nut 49 on the threaded boss 48 determines the extent of travel of the nut 69 on the threaded stud 71, when the shaft 53 is connected to the motor 10 by engagement of the clutch members 54 and 55, the projecting member 70 of the nut 69 constituting the effective element of a trip device, which accurately determines the period of time during which the mercury switch maintains the circuit to the translating device closed.

As it is characteristic of the apparatus that only a momentary closure of the energizing circuit to the solenoid is necessary, means are provided for locking the mercury switch in its circuit closing position and also holding the core of the solenoid in its upper or attracted position. To effect these operations, there is fixed to the shaft 28 a crank arm 80, which is connected by link 81 with a rock lever 82, which is fixed on shaft 38, said rock lever carrying near its outer end a stop or detent 83 projecting laterally therefrom, which is adapted to be engaged by the upper end of a bell crank lever 76 pivoted on a collar 75 clamped about the end of the cylinder 47, which lever is actuated by a spring 77, which moves the upper end of the bell crank lever under the detent 83, when the latter is elevated, thereby holding said rock lever 82 in its elevated position and locking the mercury switch in its circuit closing position and also retaining the core of the solenoid in its elevated position. The opposite end of the bell crank lever 76 projects through an opening in the cylinder 47 into the path of movement of the lug or trip member 70 of the nut 69, so that, when the nut is advanced along the screw threaded stud 71 and simultaneously rotated on said stud, the trip lug 70 ultimately engages the end of the bell crank 75

lever 76 and rocks the same against the tension of the spring 77 to move the upper end of said bell crank lever out of engagement with said detent 83, thereby permitting the weight of the core 23 of the solenoid to move rock lever 21 downward which imparts a partial rotation to shaft 28 and also to crank arm 30 and sleeve 31, which causes the mercury switch to tip in the opposite direction and break the circuit to the translating device controlled by said switch.

Fast to the shaft 28 is a rock arm 85 adapted to engage the laterally bent arm of a rock shaft 86 journaled in bearings 87 secured to the rear plate 3 and having fast thereon a yoke 88, which engages the collar formed on the head 58 of the sleeve 58'. Normally the rock arm 85 engages the rock shaft 86 to force the sleeve 58' against the tension of spring 64 to uncouple the clutch members 54 and 55, thereby disconnecting shaft 20 53 from the motor 10. When, however, the sole-noid 29 is energized, rock arm 85 is partly rotated, together with the shaft 28, thereby releasing the pressure on the bent end of the rock shaft 86 and permitting the spring 64 to force the clutch member 55 into engagement with clutch member 54 and coupling the shaft 53 to the motor 10.

The apparatus is provided with means for setting the same to retain the mercury switch in closed relation during predetermined time intervals, so that the length of time which the translating device, connected with said mercury switch, is operated, may be accurately determined and regulated. The setting device includes a shaft 90, which is journaled near one end in a bearing 30 in the plate 45 with its other end projecting through the front plate 2 and through an opening in the glass panel 5, said shaft being provided on its outer end with a knob 91 and having mounted on the squared section thereof inside 35 the glass panel a hand or pointer 92, which cooperates with a seconds scale 117 on the front plate 2, said shaft driving a train of clock gears indicated as a whole by the reference numeral 93, the final gear of said train having mounted thereon 40 a minute hand 94, which cooperates with a minute scale 118 on the front plate 2. Fixed to the shaft 90 is a broad faced gear 96, which projects through an opening in the cylinder 41 and engages the gear teeth 50 on the periphery of the 45 nut 49, which latter is in threaded engagement with the threaded boss 48, so that, when the shaft 90 is rotated, the gear 96 drives the gear nut 49 and causes the latter to traverse the threaded boss 48 axially, thereby moving the nut 49 and its 50 helical detent 51 longitudinally of the cylinder 41 and determining the rest position of the trip lug 55 70 on nut 69. The number and pitch of the threads on the axial boss 48 corresponds with those on the threaded stud 71. One complete rotation of the nut 49 will change the setting of the trip finger 70 by just one minute, as the gears 60 96 and 50 have the same number of teeth and accordingly any partial rotation of the shaft 90 will change the setting of the trip device by a given 65 number of seconds indicated by the hand 92 and the markings on the outer dial 117.

In order to hold the shaft 90 in its position of adjustment and to prevent accidental displacement of the same, which would result in changing the time of operation of the apparatus, the gear 96 is provided on its inner face with a countersink 97, which engages the beveled face of a pad of leather or the like, which bears against the face of the plate 45. Fixed to the shaft on the opposite side of the plate 45 is a

friction pad or washer 100 of leather or the like, which is engaged by a collar 99, which is forced against the element 100 by a helical spring 101 mounted on the inner end of the shaft 90 and adjusted as to tension by means of set nuts 102. 5 This forms an effective clamp, which, while permitting the shaft 90 to be readily rotated by hand, will prevent any accidental movement of the shaft.

In order to indicate the number of operations of the timing device, the latter is provided with an integrating meter or register 119 of conventional type, mounted on the rear face of the front plate, so that the indicating disks will be visible through an opening in said front plate. This register is operated by the crank arm 111, the outer end of which is connected by lift rod 112, which passes through an opening in the end of rock lever 82, said lift rod having a detent 113 thereon which is engaged by said rock lever whenever the latter is elevated, so that the register will be advanced one number for each operation of the apparatus.

As shown in Fig. 3, a gear 93', journaled on a stud mounted in the front plate 2, meshes with the first gear of the clock train 93 and is provided with a stop lug 46, which cooperates with a pin or detent 95 mounted on plate 2, said lug 46 serving to stop the rotation of the knob 91 at both the upper and lower limits of the time setting mechanism as indicated by the second and minute hands 92 and 94 on the dial scales 117 and 118. The movement of the knob 91 to bring the dial hands to stop or zero setting causes gear 96 to rotate and advance nut 49 on screw threaded boss 48 and the helical stop or detent 51 on said nut engages trip arm 70 and rotates and advances nut 69 on the threaded stud 71, so that, at the exact zero setting, the arm of bell crank 76 will just clear detent or stop 83 on arm 82. Preferably gear 93' is so adjusted that the stop lug 46 engages pin 95, when knob 91 has moved the hands 92 and 94 a slight distance to the left of the zero position in resetting the apparatus, so that the trip arm will engage the bell crank 76 and prevent the same functioning, but, when an exact zero setting is effected, by turning the knob a slight distance from the stop position in a clockwise direction, the trip arm 70 will be moved out of contact with the bell crank, so that the latter may be operated in carrying out its normal function in locking the mercury switch in its closed position, when the timing mechanism has been properly set and the electromagnet 29 is momentarily energized.

The apparatus is also designed to operate an ancillary translating device, such as a shutter 70 operating device for photographic apparatus, said device being illustrated in Figs. 11, 12, and 13. This device comprises a bracket 150 carrying a block 154 on the sides of which are mounted two solenoids 151 and 152 having a common core 153, 75

slidably mounted in a transverse opening in the block 154 and having rack teeth 153' formed on its midsection, which engage a pinion 155 fast on a shaft 156 journaled at one end in a bearing 5 in block 154 and at its opposite end in a bushing 157 threaded into an enlarged opening in the front face of the block. Fixed to the outer end of shaft 156 is a disk 158 carrying a crank pin 159 to which is attached one end of a connecting 10 rod 160, the other end of which is pivoted to a piston or plunger 161 operating in cylinder 162 extending from bracket 150, said cylinder having on its lower end a nipple 163 adapted to be connected by a flexible tube to a conventional photographic shutter. As shown, the travel of the solenoid core will carry the crank pin 159 somewhat beyond the dead center in both the upper and lower positions of said crank pin, so that accidental actuation of the piston 161 is prevented.

As conventionally illustrated in Fig. 10, the electromagnet 20, the primary translating device, represented by lamp 128, and the shutter operating device, are energized by current from the 25 main leads 120, 121 of an ordinary commercial supply of electric current. Motor 10 is connected directly across main leads 120, 121. The circuit of the magnet 20 is from main lead 121, lead 122, momentary switch 126, lead 123, coil of 30 magnet 20, lead 124, contact 37, pin 41, contact 37, lead 125 to main lead 120. The circuit of the lamp is from main lead 121, lead 126' to terminal 35' of mercury switch through the mercury to terminal 35, lead 127, lamp 128, lead 129 to main 35 lead 120. The circuit of solenoid 151 is from main lead 121, lead 122, switch 126, lead 130, coil of solenoid 151, lead 131, lead 132, contact 37', pin 41, contact 37, lead 125 to main lead 120. The circuit of solenoid 152 is from main lead 121, 40 lead 126', mercury switch, lead 127, lead 133, coil of solenoid 152, leads 131, 132, contact 37', pin 41, contact 37, lead 125 to main lead 120. As solenoid 152 is energized at the time the circuit of lamp 128 is broken at the mercury switch, 45 it is necessary that the circuit be completed between contacts 37 and 37' before it is interrupted at the mercury switch, and the initial movement of rock lever 82, when the latter is released, effects the closing of the circuit at said contacts 50 37, 37' by pin 41 and, as the breaking of the circuit at the mercury switch is not effected until the end of the release movement of the core of magnet 20 and the linkage connecting the same with rock lever 82, the opening of the circuit at 55 the mercury switch occurring after the closing of said circuit at contacts 37, 37'. The time interval between the closing of the circuit at contacts 37, 37' and the breaking of said circuit at the mercury switch is increased somewhat by the 60 time required for the body of mercury to flow from one end to the other of the tubular container, so that there is an appreciable lag in the action of the mercury switch and, as a momentary energization of solenoid 152 is all that is required, 65 the said solenoid will attract core 153 and reverse the action of the shutter operating device before the circuit is broken at the mercury switch.

The operation of the apparatus is as follows: The knob 91 is turned in a clockwise direction to 70 bring the pointers controlled thereby in registry with the desired time interval on the minute and seconds dials. If the desired time interval is measured in seconds, it will be indicated by turning the knob for a partial rotation until the 75 pointer is opposite the proper index on the sec-

onds dial. Should the time interval be measured in minutes and fractions thereof, the knob is rotated until the minute hand 94 indicates the number of minutes and the second hand the number of seconds in addition. When the timing device has been thus set, the switch 126 is closed momentarily either manually or by the movement of some part of the mechanism of the translating device with which the timing apparatus is associated. For example, if the apparatus is employed for timing photographic printing, the switch 126 may be momentarily closed during the closing movement of the printing frame by engagement of said frame or an element connected therewith with the moving element of the switch, as will be understood by those familiar with the art. The closing of the switch 126 energizes solenoid 20, drawing up the core 23 and raising rock lever 27, which imparts a partial rotation to shaft 28, which, in turn, moves rock 20 lever 30 through link 29 and tilts the mercury switch, connected to said rock lever 30, to cause the mercury to bridge the contacts in the switch terminals 35 and 35', thereby closing the circuit to the lamp 128. The movement of rock shaft 25 28 imparts a similar rocking movement to shaft 38 through crank arm 80, link 81 and lever 82 secured to said shaft 38, elevating the outer end of the rock lever 82 and permitting the upper end of bell crank 76 to pass under the stop or 30 detent 83 on the lever 82, thereby locking the several elements referred to, including the mercury switch, in their adjusted positions. The rocking movement of shaft 38 moves the switch arm 40 to disengage the bridging contact 41 with 35 the stationary contacts 37 and 37', thereby interrupting the circuit of the solenoid, so that the latter will be deenergized even if the switch 126 is left closed. The movement of rock shaft 28 causes rock arm 85 to relieve pressure on the 40 horizontal arm of rock shaft 86, permitting the spring 64 to force the clutch member 55 into engagement with clutch member 54, thereby 45 coupling the motor 10 to the shaft 53, as hereinbefore explained. The rotation of the shaft 53 causes the cage-like element secured to the end thereof to rotate therewith, thereby rotating the nut 69, which, by reason of its screw threaded engagement with the stud 71, moves axially along 50 said stud until the trip arm 70 on said nut 69 engages the end of the bell crank lock 76 and rocks said bell crank against the tension of the spring associated therewith and moves the upper end of said bell crank out of engagement with the detent 83 on the rock lever 82. This unlocks 55 the entire mechanism and permits the weight of the solenoid core to reverse the movement of all of the parts connected therewith, including lever 27, rock shaft 28, rock shaft 39 and the mercury switch, which latter is tilted to break the circuit 60 through the lamp. The reverse movement of rock shaft 38 causes the switch arm 40 to move to engage the bridging contact 41 with the terminals 37 and 37', thereby restoring the break in the solenoid circuit at this point. The reverse rocking movement of the shaft 28 causes rock arm 85 to engage the lateral arm of rock shaft 86, which causes the yoke 88 to move sleeve 58' 65 against the tension of spring 64, thereby releasing the clutch member 55 from engagement with clutch member 54 and disconnecting the motor 10 from shaft 53, which latter is now free to rotate in the opposite direction and is so rotated by the spring motor 106. This reverse rotation of the shaft 53 causes a similar rotation of the 75

nut 69 on the threaded stud 71 and also an axial movement of said nut because of the threaded engagement between the same and the stud until the trip arm 70 on said nut 69 engages the end 5 of the resilient detent 51 formed on the toothed nut 49. The upward movement of the rock lever 82, during the operation of closing the mercury switch, actuates the lift rod 112, which, in turn, actuates the register 119 to indicate the particular operation.

When the timing apparatus is employed to operate a second or ancillary translating device, such, for example, as the shutter actuating mechanism, the closing of the momentary switch 126 energizes solenoid 151, causing the same to attract its core, and the movement of the latter imparts a partial rotation to gear 155 and crank disk 158, thereby lifting piston 161 in cylinder 162 and applying suction to the shutter to open the same in the conventional manner, the circuit of said solenoid 151 being broken by the movement of rock lever 40 to withdraw contact pin from engagement with terminals 37, 37'. The shutter remains open until the mercury switch is released by the trip device at the end of the predetermined time interval to which the apparatus is adjusted, when the initial return movement of rock lever 38 causes contact pin 41 to engage contacts 37, 37', thereby closing the circuit of solenoid 152, 30 as before described, causing said solenoid to attract core 153, which rotates pinion 155 and crank shaft in the opposite direction, forcing piston 161 downward in cylinder 162, which is effective to close the shutter. This circuit is closed only momentarily and is broken at the mercury switch as soon as the latter completes its opening movement, but the lag of the said mercury switch, due to the inertia of the body of mercury therein, allows the circuit to remain 40 closed for a sufficient period of time to energize the solenoid 152.

It will be understood that the application of the timing apparatus to operate the shutter actuating device is merely exemplary and that it 45 may be employed to operate many other forms of translating devices.

The particular form of the apparatus shown is capable of effecting extremely accurate timing of the operations of translating devices of various kinds that are to be actuated for predetermined time periods varying from a few seconds to as long as five minutes, the operations of the translating device being susceptible of indefinite repetition without any variation in the time intervals whatever, as the latter are controlled and regulated by the accurate adjustment of the nut 49 on the threaded boss 28, which fixes the starting point of the trip arm 70, and a similarly accurate adjustment of the nut 69 and the movement thereof on the threaded stud 71, which movement is effected by the shaft 53, which, in turn, is driven by the synchronous motor 10.

This application is a continuation in part of application Serial No. 574,142, filed November 10, 65 1931, for Automatic electric time elapsed control mechanism.

What I claim is:

1. A timing apparatus, comprising a switch for

closing an electric circuit of a translating device to be timed, an electromagnet for moving the switch to circuit closing position, locking means for maintaining the switch in closed position independent of the energization of the electromagnet, trip mechanism for moving the locking means to inoperative position to permit movement of the switch to open position, said locking means being movable into operative position upon movement of the switch to circuit closing 10 position, means for moving the trip mechanism to an adjusted position so as to operate at the end of a predetermined time interval following the closing of the switch, a substantially constant speed motor, a clutch for connecting the motor to 15 the trip mechanism to advance the same while the switch is closed, and means for retracting the trip mechanism to its adjusted position after each tripping operation.

2. A timing apparatus, comprising a switch for closing an electric circuit of a translating device, an electromagnet for moving said switch to circuit closing position, means for locking the switch in closed position and time controlled means for releasing said locking means, said time controlled 25 means including a constant speed motor and a rotary and axially movable member operable thereby for moving said locking means to releasing position.

3. A timing apparatus, comprising a switch for closing an electric circuit of a translating device, an electromagnet to move said switch to circuit closing position, means for locking the switch in closed position, trip mechanism for releasing said locking means including a rotary and axially 35 movable member cooperable with said locking means, a constant speed motor for actuating said member, means for retracting said member after each tripping operation, and an adjustable stop to limit the return movement of said member. 40

4. A timing apparatus as described in claim 1, including means for momentarily closing the circuit of the electromagnet and additional means operable by the magnet independently of said motor for interrupting the circuit of said magnet 45 upon completion of the switch closing operation.

5. A timing apparatus for translating devices, said apparatus comprising means for momentarily closing an electric circuit of the translating device for causing said device to effect one operation, a switch for closing a second circuit of the translating device for causing said device to effect another operation, an electromagnet for effecting movement of said switch to circuit closing position, means acting after a predetermined 50 interval for opening said switch, and a second switch common to both of said circuits and controlled by the electromagnet for opening the first named circuit during circuit closing movement of the first named switch, said first named switch 55 having a lag in its opening and closing movement relative to the respectively opposite movements of said second switch, whereby in the cycle of operation of said apparatus said second switch opens before the first named switch closes and 60 the second switch closes before the first switch opens. 65

HARRY J. ATTICKS.
